DESIGN.

F. MANKEY.

MOLDING.

No. 16,524.

Patented Feb. 16, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,524, dated February 16, 1886.

Application filed November 2, 1885. Serial No. 181,711. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

Extending upon the surface of the molding 10 in a longitudinal direction, there appears a raised band, A. The opposite edges of said band are of like outline. Said outline consists in a straight portion, B, extending longitudinally the molding; a curved portion, C; a 15 straight portion, D, at right angles to B; a straight portion, E, parallel to A; a straight portion, F, parallel to D; a curved portion, G, similar to C, but reversely curved. The said

portions, in the order named, are repeated along the edges of the band. Along the center line of said band, at regular intervals, are recesses H. The outline of each recess is that of an eight-sided figure having alternating straight and inwardly-convex sides. 20

I claim—

The design for a molding, substantially as herein shown and described, consisting in the raised band A, as shown and described, and recesses H, as shown and described, disposed at regular intervals along the center line of 30 said configuration. 25

FREDERICK MANKEY.
